UNITED STATES PATENT OFFICE

GEORGE U. KOHORI, OF TACOMA, WASHINGTON

DESIGN FOR A TEA ROASTER

Application filed July 18, 1931. Serial No. 40,597. Term of patent 14 years.

To all whom it may concern:

Be it known that I, GEORGE U. KOHORI, a subject of the Emperor of Japan, residing at Tacoma, in the county of Pierce, State of Washington, have invented a new, original, and ornamental Design for Tea Roasters, of which the following is a specification, reference being had to the accompanying drawings, forming a part thereof.

In the drawings, Fig. 1 is a front elevation, a portion of the handle being omitted, for convenience of illustration; Fig. 2 is a side elevation; Fig. 3 is a plan, the handle being shown broken off; and Fig. 4 is a perspective view of a tea roaster showing my new design.

I claim:

The ornamental design for a tea roaster, as shown.

GEORGE U. KOHORI.
